New York

Application February 8, 1954, Serial No. 28,907

Term of patent 14 years

(Cl. D87—5)

To all whom it may concern:

Be it known that we, Roland L. Barratt and Martin Aaron, have invented a new, original, and ornamental Design for Carrying Case, of which the following is a specification, reference being had to the accompanying drawing, forming a part hereof.

Fig. 1 is a side view in elevation of a carrying case showing our new design; and

Fig. 2 is an end view in elevation.

The dominant features of the design reside in the portions shown in full lines of the drawing, the side and end not shown being identical to those shown.

We claim:

The ornamental design for a carrying case, as shown and described.
